ware

Application February 26, 1929. Serial No. 342,859

12 Claims. (Cl. 202—151)

Our invention relates to coke-oven apparatus and particularly to safety devices for the operating mechanisms of coking retort ovens.

One object of our invention is to provide simple and effective means for preventing the formation of explosive mixtures in the waste gas flues or the stacks of coke-oven batteries by reason of the failure of any part of the reversing mechanism to properly perform its normal functions.

A further object of our invention is to provide means for interlocking the mechanisms for controlling the flow of air, fuel gas and waste gas in such manner that abnormal combinations of such gaseous fluids are prevented in case of failure of any part of the controlling mechanism.

A further object of our invention is to provide simple and efficient mechanical means for so interlocking the usual oppositely movable rods for controlling the valves or dampers of coking retort ovens that the movement of one of the rods to open certain of the valves is prevented when the other of the rods occupies a predetermined position.

A still further object of our invention is to provide simple means for mechanically interlocking the reversing mechanism of coking retort ovens whereby it is impossible for certain sets of the valves to simultaneously occupy their open positions.

In the operation of coking retort ovens, it is customary to supply air to half of the inlet regenerators and producer gas to the other half of the inlet regenerators and to withdraw waste gases from all of the outlet regenerators. The connections for the regenerators are periodically reversed by automatic mechanism which closes the valves or dampers for the waste gas regenerators and also closes the respective valves or dampers for the air and the gas regenerators. The air and the gas valves for the regenerators that have been transmitting waste gases are then opened to admit air and gas, as the case may be, and the regenerators that have been previously supplied with air and gas are now operated as waste gas regenerators.

It will be appreciated that in case the valves for the regenerators operate in improper sequence, a mixture of fuel gas and hot waste gases may result, with the possibility of an explosion in the waste gas main or in the stack. Such mixture may occur if, for example, the fuel gas valve is opened before the waste gas valve is closed, or if the waste gas valve opens before the fuel gas valve is closed. In either case, the fuel gas flows

from the gas main through the gas valve and out through the waste gas valve into the waste gas flue.

It is the purpose of the present invention to provide means for positively insuring that the valves for controlling the gas supply and the outlets of the waste gases from the regenerators to the stack operate in such sequence that explosive mixtures cannot occur. The usual gas rod and the air and waste gas rod of the reversing mechanism, and which rods are movable in opposite directions, are so interlocked by mechanical means that the movement of the air and waste gas rod to open the corresponding valves is prevented when the gas rod occupies its position corresponding to the open positions of the gas valves of the same regenerators. Also, each of the rods is provided with a cable for connection to the reversing machine and with a slack cable switch in circuit with the reversing machine motor. The switches operate to stop the motor in case of breakage of either of the cables.

The details of our invention will be described in connection with the accompanying drawings, in which

Fig. 1 is a side elevational view of a coke-oven battery provided with apparatus of our invention, parts being broken away;

Fig. 2 is an elevational view in enlarged detail of the interlocking mechanism and associated parts;

Fig. 3 is a view similar to Fig. 2, illustrating diagrammatically the several positions of the interlocking mechanism;

Fig. 4 is a vertical sectional view of a portion of a coke-oven battery and the valve mechanisms for controlling the admission of air and gas thereto and the flow of waste gases therefrom;

Fig. 5 is a side elevational view of slack cable switches and portions of the reversing apparatus;

Fig. 6 is a perspective view of a modified form of interlock in which cables are substituted for mechanical levers;

Figs. 7 and 8 are side elevational views of the apparatus of Fig. 6; and

Fig. 9 is a vertical sectional elevation taken longitudinally of a coke-oven battery.

Reference may now be had to Figs. 1, 2 and 3, in which are illustrated the reversing mechanism of a coke-oven battery and the associated apparatus.

A coke-oven battery 1, only a portion of which is shown, comprises the usual side walls 2, oven

chambers 3, gas-combustion heating means or flues 3', and buckstays 4. Along the side of the battery are provided a series of valve mechanisms 5 for controlling the admission of air and gas to the battery for combustion therein and for controlling the exhausting of the waste gases from the battery.

In accordance with usual practice, half of the valve mechanisms 5 are arranged to transmit either air or waste gas while the other valve mechanisms are arranged to transmit either fuel gas or waste gas.

The positions of the several valves for controlling the air inlets, the gas inlets and the outlets for waste gases are controlled by two horizontal rods 6 and 7. The rod 6 controls the valves for admitting fuel gas and it will be hereinafter referred to as the gas rod. The rod 7 controls both the valves for the air inlets and the waste gas outlets and will be hereinafter referred to as the air and waste gas rod.

The positions of the gas rods and air and waste gas rods are controlled by a reversing mechanism 8 of usual type which is in practice time-controlled to periodically reverse the positions of the rods and correspondingly reverse the positions of the several valves controlled by the rods. The reversing mechanism 8 is connected to the respective rods by cables 9 and 10 which pass over sheave wheels 11 and 12. At the opposite ends of the rods 6 and 7, cables 13 and 14 connected thereto pass over sheave wheels 15 and 16 and are provided at their outer and lower ends with counterweights 17 and 18.

In the actuation of the rods 6 and 7, the reversing mechanism 8 is operated by an electric motor (not shown) to pull one of the rods to the right, as viewed in Fig. 1, while the cable connected to the other rod is paid out to permit the corresponding counterweight to pull the latter rod to the left. It will be readily appreciated that the normal operation of the rods 6 and 7 to reverse the positions of the corresponding valve could not occur if either of the cables 9, 10, 13 or 14 were broken or if the counterweights 17 and 18 were obstructed in their downward movement. The breaking of one or both of the rods would also cause abnormal operation of the reversing apparatus. Such abnormal operation might admit fuel gas into the ducts for connecting waste gas with the consequent danger of causing an explosion in the waste gas flue or the stack.

In order to positively prevent the valve mechanism connected to the rods 6 and 7 from assuming positions that are inconsistent with the safe operation of the battery, we have provided a mechanical interlock 20 for preventing the actuation of the rods to cause improper operation of the valves. The interlock 20 comprises three steel arms or levers 21, 22 and 23 that cooperate with blocks 24 and 25 that are respectively connected to the rods 6 and 7. The lever 21 has a stationary pivotal support at 26 substantially midway between the rods 6 and 7. The lever 22 is pivoted at one end on the pivotal support 26, the other end being connected to the lower end of lever 23, the upper end of the latter being pivotally connected to the rod 6.

As clearly shown in Fig. 2, the upper end of the lever 21 is adapted to engage the block 24 under certain conditions while the lower end of the lever 22 is adapted to engage a shoulder on the block 25 under certain other conditions.

Reference may now be had to Fig. 4, in which

are shown the details of the means for supplying gas and air to one of the regenerators 30' and for exhausting waste gases therefrom, including one of the valve mechanisms 5. A gas main 28 for conveying producer gas is connected through a duct 29 to the sole flue 30 or common passageway for conveying gas to one of the regenerators 30' of the battery and thence to its combustion means or flues 3 and for conveying waste gas therefrom, the flow of gas being controlled by a manually-operable valve 31 and valved gas inlet means comprising a valve 32 that is controlled by the gas rod 6.

The gas rod 6 is connected to the valve 32 by means of a chain 33, a bell crank lever 34 and a link 35 that has a pin-and-slot connection to a bell-crank lever 36 that is directly connected to the valve 32. The manually-operable valve 31 is adjusted prior to the operation of the battery by a hand-wheel 37 since, as previously stated, gas is supplied to the battery through half of the inlet regenerators at any given time.

The admission of air to the sole flue or common passageway 30, in case the corresponding regenerator is used as an air regenerator is controlled by a valve or damper 38 of substantially rectangular form, certain of these dampers being shown in their open positions in Fig. 1. The air and waste gas rod 7 is connected to the valve 38 by a chain 39, a lever 40 that is connected to a rock shaft 41, a lever arm 42, a vertical link 43, a lever arm 44 and a rock shaft 45 that is connected to the valve 38 by a lever arm 46. The latter is provided at its outer or left-hand end, as shown in Fig. 4, with a clamp comprising a pivoted bolt 47 and a thumb nut 48 whereby the valve 38 may be securely fastened in its closed position. This clamp is employed when the corresponding regenerator is used as a gas regenerator in which case no air is admitted.

The connection of the sole flue 30 to a vertical duct 50 for conducting waste gases to the waste gas flue and stack is controlled by valved waste gas outlet means comprising a valve 51 that is operated by a lever 52 connected to the rock shaft 41. It will be noted that the air valve 38 and the waste gas valve 51 are both connected to the rock shaft 41 but when the regenerator is employed as a gas regenerator rather than air, the valve 38 is disconnected from the rock shaft 41 in order that the waste gas valve 51 may operate. The lever arm 40 is provided with a counterweight 53 for insuring the opening of the air valve 38 when the latter is connected for operation upon the movement of the rod 7 to permit the waste gas valve 51 to close.

The sequence of operation of the several valves shown in Fig. 4 will be described in connection with the actuation of the rods 6 and 7, this sequence being typical of all of the similar mechanisms for controlling the heating system of the battery. It may be assumed that the gas rod 6 is in its extreme position to the left and that the air and waste gas rod is in its extreme position to the right, as viewed in Fig. 1, in which case the various valve mechanisms will transmit gas, air or waste gases in accordance with the corresponding positions of the respective valve mechanisms, as indicated by the legends G, A and WG, respectively. The valve mechanism of Fig. 4 is adjusted for permitting the exhausting of waste gases to the stack through the open valve 51 and the duct 50.

The initial operation of the reversing machine 8 actuates the gas rod 6 relatively quickly to the right to its middle or neutral position to close the previously open gas valves 32 controlled by it. 5 The air and waste gas rod 7 is then actuated continuously to the left to first close the air valves 38 and the waste gas valves 51 of such valve mechanisms as are open and then to open the air valves 38 of one half of the inlet regenerators which had 10 previously transmitted waste gases and to open the waste gas valves 51 of all of the regenerators which had previously been serving as inlet regenerators for either gas or air. The gas rod 6 then quickly completes its movement to the right 15 to open the gas valves 32 of the other half of the inlet regenerators.

Upon the succeeding reversal, similar movements of the rods 6 and 7 produce corresponding results. The gas rod is moved to the left to its 20 middle position to close all of the open gas valves. The air and waste gas rod 7 is then moved to the right to close all of the open valves controlled by it and to continue its motion until the air valve of the inlet regenerators are opened and the waste 25 gas valves of the outlet regenerators are also opened. The gas rod is then moved to the left to open the gas valves of the other inlet regenerators.

In Fig. 5 is illustrated a slack cable switch for 29 each of the cables 9 and 10 for respectively connecting the rods 6 and 7 to the reversing machine 8. This arrangement comprises two switches 53 and 54 and wires 53' and 54' and 54'' that are in series with each other and that are in circuit with the motor M for driving the reversing machines 8. Each of the switches is controlled by a weight 55 suspended from a pulley 56 and connected to the 35 respective switches by an arm 57. The operation of the slack cable switch mechanism occurs when either of the cables 9 and 10 is sufficiently slack to permit the corresponding arm 57 to open the switch to which it is connected, whereupon the reversing machine motor stops by reason of the 40 interruption of its circuit.

During the normal operation of the reversing mechanism, the positions of the rods 6 and 7 and the valves controlled thereby are reversed periodically, for example, every half hour. The interlock 20 has no effect upon the operation of the rods 6 and 7 except in case of failure which may be due to any of the following causes or combination of causes:

(1) Failure of cable on reversing machine end of either gas or air and waste gas rod.

(2) Failure of cable on counterweight end of either control rod.

(3) Failure of either control rod between the cables on the ends of the same.

(4) Counterweights on either control rod "hanging up" or falling off.

(5) Any combination of the foregoing.

When the gas rod is in its left-hand position and the air and waste gas rod is in its right-hand position as shown in Figs. 1, 2 and 3, the respective levers 21, 22 and 23 and the blocks 24 and 25 will occupy their respective positions indicated by full lines. In case of a break in the cable at the reversing machine end of the gas rod 6 while the rods are stationary, nothing happens. If the reversing machine starts to reverse the position of the rods, movement of the rod 7 to the left is prevented since the block 25 engages the lever 22 with the result that the cable 10 will be slack and the switch 54 opens to stop the reversing machine motor.

In case of a break in the cable 10 on the reversing machine end of the air and waste gas rod 7, the block 5 will engage the lever 22 and the rod 7 will be held in its right-hand position.

When the positions of the rods 6 and 7 are reversed from those shown in Figs. 1, 2 and 3, the levers 21, 22 and 23 and the blocks 24 and 25 occupy their corresponding positions as illustrated by dot-and-dash lines in Fig. 3. Under these conditions, a break in the cable 10 will not affect the position of the air and waste gas rod 7 since it is in its left-hand position. If the cable 9 on the gas rod breaks, the block 24 and the gas rod 6 will be moved by the counterweight to the left to its intermediate position where it engages the lever 21, the latter being held at its opposite end against the block 25 which is in its extreme left-hand position. Thus, the gas rod 6 will be stopped with all of the gas valves 32 closed.

The foregoing examples are typical of the operation of the interlock for the prevention of the simultaneous open positions of the gas valves 32 and the waste gas valves 51 in the same valve or damper mechanism. The following table sets forth all of the possibilities of failures in the reversing mechanism and the manner in which the safety devices of our invention operate to prevent abnormal relative positions of the several valves:

Failure	Results	
	Not reversing	Starting to reverse
Gas counterweight up air and W. G. cwt. down		
1. Break at counterweight end of gas rods	Nothing	Slack cable switch stops machine
2. Break at counterweight end of air rods	Nothing	Complete reversal, slack cable switch will stop machine at beginning of next reverse
3. Break in gas rods between reversing machine and interlock	Cwt. pulls rod interlock. All gas off	Counterweight pulls rod to interlock. All gas off
4. Gas counterweight hang up		Slack cable switch stops machine leaving same sequence as before reversal
5. Break in air rods between reversing machine and interlock	Nothing	Cable switch stops machine in neutral

Failure	Results	
	Not reversing	Starting to reverse
Air and W. G. counterweight up. Gas counterweight down		
1. Break at counterweight end of air rods	Nothing	Cable switch stops machine
2. Break at counterweight end of gas rods	Nothing	Complete reversal, slack cable switch will stop machine on next reverse
3. Break in air rods between reversing machine and interlock	Interlock holds rod, valves remain in same sequence	Interlock holds rod and valves remain in same sequence. Slack cable switch stops machine or complete reverse takes place. Slack cable switch stops machine on next reverse
4. Air counterweight hang up		Cable switch stops machine, leaving same sequence as before
5. Break in gas rods between reversing machine and interlock	Nothing	Cable switch stops machine

	Break occurring at half of travel during reversing	Results
5	Gas counterweight going down air and W. G.—going up	
10	1. Gas counterweight. Hang up or drop off 2. Break at machine end of gas rods	Cable switch stops machine—gas is off-air and W.G. partly open. Gas rod would be stopped in neutral by interlock, leaving all gas valves closed—switch would stop machine. Counterweight would drag W. G. rod back; cable switch would stop machine leaving all gas valves closed.
15	3. Break at machine end on air and W. G. rods 4. Break in gas rod in the middle of battery 5. Break in air rod in the middle of battery	Interlock holds rod—all gas off—cable switch stops machine. Counterweight would drag rod back from break against button on interlock, and would hold against counterweight on gas rod with gas off—cable switch stops machine. Nothing
20	6. Break at counterweight end of air rods Break at counterweight end of gas rods	Slack cable switches stops machine

*Counterweight air going down
Gas going up—counterweight*

25 Same as preceding

30 A modification of the interlock mechanism is shown in Figs. 6, 7 and 8, in which the mechanical devices are replaced by an arrangement comprising two cables 59 and 60, the former being connected to the counterweights 17 and 18, a stationary pulley 61 and a movable pulley 62. The movable pulley 62 is secured to one end of a lever 63 having a pivotal support at 64, the other end of the lever 63 being connected to the cable 35 60. The cable 60 is connected to the counterweight 17.

40 When the rods 6 and 7 and the connected parts are in the respective positions in which they are shown in Fig. 7, a failure on the reversing-machine side of the points of attachment of the safety cables does not cause anything to happen since the gas rod is in its extreme left-hand position away from the reversing machine. In case 45 of a similar failure on the air and waste-gas rod 7, the safety cable 59 would hold the rod 7 in its original position, thereby preventing the counterweight 18 from pulling the air and waste-gas rod 7 into its left-hand position. The prevention of this movement of the rod 7 prevents the 50 mixture of fuel gas and waste gas since the gas rod is already in its left-hand position and if the air and waste-gas rod 7 were actuated to the left at this time, both gas and air would be admitted into the waste gas flue.

55 When the rods 6 and 7 and their connected parts are in the positions shown in Fig. 8, a failure of the air-reversing mechanism on the reversing-machine side of the points of attachment of the safety cables can cause no harm since the air and waste-gas rod is already in its extreme position from the reversing machine. However, in case of failure in the gas-reversing mechanism, there is just sufficient slack in the 60 cable 59 to allow the gas rod 6 to drop back to its neutral position since the cable 60 is slack at this time, as illustrated. Accordingly, no abnormal flow of gas into the waste gas flue can occur because all of the gas valves are closed.

70 If, in either of the foregoing cases, the break or failure is not discovered before the succeeding reverse of reverses, no harm will be done.

In case of failure of the reversing mechanism beyond the points at which the safety cables 75 are attached, no harm can occur until a reverse

takes place. Thereupon, the cables connected to the reversing machine will become slack and the slack cable switches will trip out, permitting the reversing machine to operate to its middle or neutral position.

It will be appreciated by those skilled in the art relating to the construction and operation of coke-oven batteries that we have provided a simple and efficient mechanism for positively preventing the formation of explosive mixtures in the waste-gas flue and stack by preventing the adjustment of the gas valves to their open positions when the waste-gas valves of the corresponding regenerators are open to connect the regenerators to the stack.

80 85 90 The importance of an arrangement whereby any failure in any part of the reversing mechanism will be prevented from causing abnormal or inconsistent positions of the reversing mechanisms will be readily understood in view of the heavy investment in the installation of the coke-oven plant and the danger to life in case of an explosion.

95 While we have shown and described our invention in its preferred form, it is not limited thereto other than is expressed in the appended claims.

100 I claim as my invention:

1. A coke oven apparatus comprising gas-combustion heating means therefor; a common passage for conveying gas to the combustion means and for conveying waste gas therefrom; valved gas-inlet means for conveying gas for the combustion means to said common passage; valved waste-gas-outlet means for conveying waste gas of the combustion means from said common passage; reversing mechanism for controlling the positions of the valves of said valved means, and interlocking means for preventing the opening of the valve of one of the valve means 110 when the valve of the other valved means is open.

- bustion heating means therefor, a regenerator for supplying gas to the combustion means and for exhaust of waste gas therefrom and having gas supply means for supplying gas thereto for conveyance to said combustion means and a waste gas main connected thereto for conveying waste gas of said combustion means from said regenerator, valves for controlling said gas supply means and said main, respectively, reversing mechanism for controlling the positions of said valves, and interlocking means for preventing said valves from occupying open positions simultaneously, said interlocking means comprising members connected to oppositely movable parts of said reversing mechanism and levers for engaging said members to prevent certain movements of one of said parts relatively to the other. 5
5. Coke oven apparatus comprising gas combustion heating means therefor, means for supplying air and gas to the combustion means, means for conducting waste gases from the combustion means, valves for controlling the supplying means and the conducting means, respectively, reversing means for alternately opening and closing certain of said valves while closing and opening certain other of said valves and interlocking means for preventing the operation of said mechanism to open all of said valves simultaneously. 20
6. Coke oven apparatus comprising gas combustion heating means therefor, passages for conveying air and gas thereto and for conveying waste gas therefrom, separate means for supplying air and gas to said passages, means for conducting waste gases from said passages, valves for controlling the supplying means and the conducting means, respectively, reversing means comprising two oppositely movable members, one of which controls the valves for the air supply means and the waste gas conducting means and the other of which controls the valves for the gas supply means, and means for interconnecting said movable members to prevent their simultaneously occupying positions corresponding to the open positions of the valves controlled thereby for controlling inflow to and outflow from the same openings. 35
7. Coke oven apparatus comprising valve-reversing mechanism including two oppositely movable members, a block on each of said members and a plurality of levers for coacting with said blocks to prevent movement of one of said members when the other of said members occupies a predetermined position. 50
8. Coke oven apparatus comprising valve-reversing mechanism including two oppositely movable members, a block on each of said members, 60
- a pivotally mounted bar for coacting with the block on one of said movable members and operatively connected to the other of said movable members, whereby it is moved into and out of the path of the coacting block and a lever for coacting with both of said blocks for limiting the movements of said movable members. 80
9. Coke oven apparatus comprising reversing mechanism having two oppositely movable members, a block on each of said members, a lever for coacting with said blocks for limiting movements of said members in one direction, a bar for engaging a block on one of said members, and means for connecting said bar to the other of said members whereby the engagement of said bar and said one block is dependent upon the relative positions of said members. 85
10. Coke oven apparatus comprising gas combustion heating means therefor, means for supplying air to the combustion means, means for supplying gas to the combustion means, means for conducting waste gases from the combustion means, valves for controlling the supplying means and said conducting means, respectively, reversing means for said valves comprising oppositely movable members one of which controls the air supply and waste gas conducting valves and the other of which controls the gas supply valves, a block on each of said movable members, a lever for coacting with said blocks for limiting the relative movements of said members and a bar connected to the gas supply controlling member and movable thereby into and out of the path of the block on the other movable member. 95
11. Coke oven apparatus comprising reversing mechanism having two oppositely movable members, and a motor for actuating said members, mechanical means for interlocking said members against relative movement upon failure of one of said members to be actuated by said motor when the other responds to actuation and electrical switch means controlled by said members and operable upon failure of said members as aforesaid to control said motor so as to discontinue actuation of said members by said motor. 100
12. Coke oven apparatus comprising gas combustion heating means therefor, valved means for conveying gas to the combustion means, valved means for conveying waste gas from the combustion means, reversing means adapted for opening and closing the valves of both of said valved means, and locking means adapted for locking the reversing means for preventing the valves of both of said valved means from being opened simultaneously by the reversing means. 115
